UNITED STATES PATENT OFFICE.

FRANK MULIG, OF LYNDORA, PENNSYLVANIA, ASSIGNEE OF ONE-HALF TO JOHN H. OTT, OF LYNDORA, PENNSYLVANIA.

TOY.

1,266,847.

Specification of Letters Patent. Patented May 21, 1918.

Application filed January 10, 1918. Serial No. 211,210.

To all whom it may concern:

Be it known that I, FRANK MULIG, a citizen of the United States, residing at Lyndora, in the county of Butler and State of Pennsylvania, have invented certain new and useful Improvements in Toys; and I do declare the following to be a full, clear, and exact description of the invention, such as will enable others skilled in the art to 10 which it appertains to make and use the same.

My invention has for its object to provide a highly amusing toy which may be inexpensively manufactured and sold at small 15 cost, said toy embodying a gun for shooting marbles and the like, and preferably a whistle.

With the foregoing object in view the invention resides in the device herein described and claimed and shown in the accompanying drawing wherein:

Figures 1 and 2 are perspective views showing two ways in which the gun may be fired;

Fig. 3 is a perspective of the device in normal position;

Fig. 4 is a longitudinal section; and,

Fig. 5 is a transverse section on the plane of the line 5—5 of Fig. 4.

In the drawing above briefly described, the numeral 1 designates a straight preferably rectangular block of wood or other suitable material, said block having a central bore 2 with which a pair of longitudinal slots 3 communicate, said slots being formed in opposite sides of the block and being of less width than the diameter of the bore 2 as seen in Fig. 4.

A combined hammer and trigger in the form of a flat straight bar 4 of wood or other appropriate material passes across the bore 2 and through the front ends of the slots 3, the ends of the bar being widened to form heads 5 of a size to prevent removal of said bar until it is turned to disposed its flat sides parallel to the sides of the slots. These heads however are spaced sufficiently from the block 1 to permit the bar to slide longitudinally a considerable distance to 50 increase its leverage against a coiled spring 6 which bears against its rear side.

The spring 6 is slipped into the bore 2

before the bar 4 is inserted and when said spring is slightly compressed by insertion of said bar, its tension will hold the latter normally against the front ends of the slots 3 as seen in Fig. 4, the rear end of said spring being positioned against the inner end of the bore. Spring 6 engages the bore 2 rather snugly and is of sufficient size to prevent loss 60 through the slots 3.

As seen clearly in the drawings, the ends of the slots are spaced sufficiently from the front end of the block 1, to locate the bar 4 at a suitable distance from said end to 65 permit the reception of a marble or the like 7 in the front end of the bore. Either head 5 may be pulled rearwardly by the fore finger (Fig. 1) or the thumb (Fig. 2) and thus the spring 6 will be compressed by tilting of bar 4 and will return said bar to normal position when the same is released. The spring thus serves to force the bar against the missile 7 and the latter is consequently impelled from the gun with considerable 75 force.

In playing certain games, it is desirable to use an alarm or signal in addition to the gun and I have therefore equipped the rear end of the block 1 with a simple form 80 of whistle as seen at 8, but it is to be understood that the device may well be manufactured without this feature.

The article is extremely simple and may therefore be manufactured and sold for a 85 small amount, yet it will afford considerable amusement.

I claim:

A toy of the type described comprising an elongated block having a longitudinal bore 90 opening through its front end, two opposite sides of said block each having a longitudinal slot opening into said bore, said slots being of less width than the diameter of said bore, a combined hammer and trigger in the 95 form of a flat bar passing through the front ends of said slots and across said bore, the ends of said bar being increased in width to form heads for preventing removal of said bar until it is turned to position its flat sides 100 parallel with the sides of the slots, said heads being spaced from said block, and a coiled spring in said bore in rear of said bar, one end of said spring abutting said

bar and the other end thereof being disposed against the inner end of said bore, said spring being greater in diameter than the width of said slots to prevent loss there-
5 through.

In testimony whereof I have hereunto set

my hand in the presence of two subscribing witnesses.

FRANK MULIG.
